CLARENCE A. BATES, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

PUSH-SWITCH.

1,095,138.

Specification of Letters Patent. Patented Apr. 28, 1914.

Application filed June 26, 1913. Serial No. 775,940.

To all whom it may concern:

Be it known that I, CLARENCE A. BATES, a citizen of the United States of America, and residing at Bridgeport, in the county 5 of Fairfield and State of Connecticut, have invented a certain new and useful Improvement in Push-Switches, of which the following is a specification.

My invention relates to electric push 10 switches and particularly to pendant electric switches, the object of my invention being to provide a simple and efficient mechanism of improved type for switches of this character.

15 In the accompanying drawings, Figure 1 is a vertical section through a pendant switch in which my invention is illustratively embodied; Fig. 2 is a side elevation thereof partially broken away to show the 20 position of the push button at the moment just preceding the making of the contact thereby; and Fig. 3 is a dropped elevation partially in section showing the construction of the push button mechanism.

25 The switch here illustrated is of the type commonly used in hospitals and installed at the side of the beds within reach of the patient to enable the latter to readily call an attendant in case of need. The switch 30 casing 5 comprises the usual pear-shaped handle of insulation with longitudinal perforation to admit the wires 6 and 7 at one end and the push button 8 at the other end. A radial perforation 9 permits the insertion 35 of a set screw 10 which engages the metallic thimble 11 which forms the frame of the switch mechanism and holds the latter in assembled position within the handle 5. The 40 enlarged end of the handle is preferably flat or dished at 12 to correspond to the dished lower face of the annulus 13 at the lower end of the cylindrical switch frame 11 which forms a stop engaging the internal shoulder 14, thus positioning the push switch frame 45 within the handle 5.

Wire terminals 15 and 16 mounted at the upper end of the insulating button 17 seated at the upper end of the thimble 11 and held in position by set screws 18, are provided 50. with inwardly projecting flanges 19 adapted to be engaged by the push pin mechanism. The push button 8 and its contacts 20, 21, are so proportioned with relation to the contacts 19 that the button 8 must be 55 depressed beyond the lower level of the

handle 5 before the contacts are brought into engagement with the terminal flanges 19. The position of the button 8 is shown in Fig. 2 at the moment just preceding the engagement of the contacts on the push button with the flanges 19 on the wire terminals. It is thus impossible to accidentally close the signal circuit, should the handle 5 be dropped upon the floor, since even should the handle fall with its push button end 60 flat on the floor, the push button being thereby depressed, the circuit would still not be closed, since the button contacts will not engage the terminal flanges 19 until the button 8 has been pressed in beyond the plane 65 of the lower edges of the handle 5. It has heretofore been customary also to make the push button contact in the form of a plunger which engages spring contacts on the terminals 15, 16. It frequently happens that 70 the plunger is engaged with such friction that it becomes wedged in position and fails to return to the normal open position of the switch. To avoid this difficulty I have mounted upon the button a pair of spring 75 contacts 20, 21, formed from a strip of spring sheet metal bent to shape. As will be noted from Fig. 3 the upper ends of these contacts are inclined toward each other so that they enter between the flanges 19 on 80 the wire terminals 15, 16. As the result of this construction, the terminals are pressed toward each other in the closed position of the switch and their tendency is to force 85 the button out of its engaging position so that there is no danger of the contacts thereon becoming frictionally engaged and wedged between the contacts on the terminals 15, 16. To permit the button to swivel 90 with relation to its contacts 20, 21, the latter are rotatably secured thereon by means of a spread rivet 22 which passes through a perforation in the base 23 of the contacts. The passage 30 in the upper portion of 95 the insulating button 17 is rectangular in cross section as usual, so that the contacts 20, 21 are constantly held in position to engage the terminals 19.

As above stated the wire terminals 15 and 16 are carried by a button 17 of insulating material which is cylindrically shouldered at 24 to enter the thimble 11. It is also internally shouldered at 25 to form the seat for one end of the coil spring 26 which bears at its other end against the shoulder 100 105 110

27 on the push button, thus tending to constantly force the latter outward into the open position of the switch. The internal shoulder 28 on the thimble 11 prevents the 5 escape of the push button 8 under the influence of the spring 26.

Various modifications of the construction described will readily suggest themselves and I do not limit myself to the precise 10 details shown which are to be regarded as merely an illustrative embodiment of my invention.

I claim as my invention:

1. A pendant switch of the character described, comprising a body of insulating material adapted to be grasped by the hand, said body being longitudinally perforated to afford a switch chamber opening to one end and a wire entrance aperture opening 20 to the opposite end thereof, a switch frame, wire and switch terminals carried thereby, means for mounting said frame within the switch chamber and a push button slidably mounted in said frame and carrying a switch 25 piece adapted to electrically connect the switch terminals only upon the depression of said button inwardly beyond the plane of the end of the switch body.

2. A pendant push button switch having 30 an insulating body adapted to be grasped in the hand and longitudinally perforated to admit leading-in wires at one end and a push button at the opposite end, a switch frame within the body, binding screw wire 35 terminals carried thereby and projecting from the frame toward the wire entrance end of the body, switch terminal flanges struck from said wire terminals and angled toward each other, a push button sliding in 40 said frame and spring contacts carried by said button and adapted to enter between the said switch terminal flanges to complete the switch circuit, substantially as described.

3. A pendant push button switch having a 45 body of insulating material adapted to be

grasped by the hand, and chambered to receive a switch frame at one end and leading-in wires at the other end, a switch frame mounted in said body and carrying stationary switch terminals, a push button 50 slidable in said frame, a contact piece mounted on the inner end of said button and swiveling with relation thereto and means for guiding said contact piece into engagement with the switch terminals and holding it 55 against rotation, whereby said push button is free to swivel with relation to said contact piece without displacing it from position to engage the stationary switch terminals, substantially as described. 60

4. A pendant switch of the character described comprising a body of insulating material adapted to be grasped by the hand, said body being longitudinally perforated to afford a switch chamber opening to one 65 end and a wire entrance aperture opening to the opposite end thereof, an internal shoulder at the switch end of the body, a switch frame seated against said shoulder, means for holding said frame in position, an insulating button carried at the inner end of said frame, a pair of wire terminals mounted on said insulating button and projecting toward the wire entrance end of the switch body, switch terminals electrically connected with said wire terminals, a push button working in the outer end of said frame, a spring confined between said insulating button and push button and serving to constantly force the latter outward, together 70 with spring switch contacts adapted to enter between said switch terminals to complete the switch circuit, substantially as described.

In testimony whereof I have signed my name to this specification, in the presence 85 of two subscribing witnesses.

CLARENCE A. BATES.
